United States Patent Office

Des. 218,515

Patented Aug. 25, 1970

218,515

BAG SEALER

Theodore J. Tomaiuolo, 44 Fairfield Ave.,
Hartford, Conn. 06141

Filed May 1, 1969, Ser. No. 16,974

Term of patent 14 years

Int. Cl. D9—08

U.S. Cl. D9—252

FIG. 1

FIG. 2

FIG. 3

FIG. 4

FIG. 5

FIG. 6

FIG. 1 is a perspective view of a bag sealer, showing my new design;

FIG. 2 is a side elevational view, the opposite side being a mirror image of the side shown;

FIG. 3 is an end elevational view looking from the right of FIG. 2;

FIG. 4 is an end elevational view looking from the left of FIG. 2;

FIG. 5 is a top plan view; and

FIG. 6 is a bottom plan view thereof.

I claim:

The ornamental design for a bag sealer, substantially as shown and described.
